TOOL FOR GRINDING VALVES

Lawrence O. Beard, Lancaster, Pa.

Application January 18, 1935, Serial No. 2,439

5 Claims. (Cl. 51—185)

My invention relates to a tool for grinding valves and more particularly the conical valves in the motor blocks of internal combustion engines.

5 The principal object of my invention is to provide a grinding tool for conical valves which will present a plurality of spaced relatively narrow grinding surfaces, thus speeding up the grinding action.

10 Another object is to provide a tool having an abrasive element removably mounted therein which is adapted to be shifted when worn to present new grinding surfaces.

15 A further object is to provide a tool whereby a uniform grinding or cutting action is assured with a minimum application of force.

These and other objects will be apparent when the specification is considered with the accompanying drawing, in which:

20 Figure 1 is a side view of the tool;

Figure 2 is a plan view of the assembled tool;

Figure 3 is an enlarged cross sectional elevation of the assembled tool;

25 Figure 4 is a plan view of the abrasive disk; and

Figure 5 is a section through a portion of the conical grinding shell.

Referring more particularly to the drawing, the numeral 1 designates the tool generally comprising a substantially conical shell 2, preferably formed of a die casting or the like. The shell has a truncated, conical body portion 3 that tapers to a hollow extension 4 at one end, which extension has a bore 5 extending therethrough 30 for the reception of a stem 6 of a poppet valve 7.

The conical body portion 3 of the shell 2 is provided with a plurality of substantially U-shaped, outwardly flaring radial folds 9, preferably five in number, extending from the upper edge or lip 40 10 of the shell to the end of the conical body portion at a slightly decreased pitch from that of the body portion. These folds form and are interposed between a plurality of spaced flat working areas or faces 8. These working faces, which merge with the side walls 11 of the U-shaped folds 9, are ground down to provide flat narrow V-shaped valve engaging portions 12 at the inner or lower ends of the working faces 8, and to provide a flat supporting surface 13, at 45 each side thereof for a purpose presently described.

A thin circular disk of abrasive material, such as emery cloth or paper 14, having a centrally disposed aperture 15, constitutes the abrasive element for grinding the valve 7. The abrasive

14 is seated within the shell 2 and caused to conform closely to the contour of the latter by means of a substantially rigid or semi-rigid clamping member or spider 16 formed of slightly yielding metal. Clamping member 16 comprises a narrow annular or ring-like portion 17, the bore and diameter of which are respectively just sufficient to permit of the clamping member being sleeved over a slotted bushing or sleeve 18 which is positioned in and extends through the bore 5 10 of the extension 4. The bushing 18 is provided with a collar 19 on the upper end thereof which is adapted to engage the ring-like portion 17 and retain the clamping member 16 in position. The lower end of the bushing is externally threaded 15 as at 20, to receive thereon the clamp nut 21 for tightly clamping the collar 19 of the bushing 18 against the ring-like portion 17 of the clamping member. An adapter or bushing 22, adapted to be snugly sleeved within the bushing 18, 20 is provided with an enlarged knurled lower end portion 23 which contacts the lower end of the threaded bushing 18 when the parts are assembled. The stem 6 of the valve is adapted to be snugly received in the bore of the bush- 25 ing 22.

Projecting upwardly and outwardly from the annulus 17 of clamping member 16, are a plurality of arms 24, one for each fold 9, in which fold these arms are adapted to snugly fit when the latter, together with the adjacent portions of the abrasive disk, are pressed thereinto. The arms are V-shaped and tapered to snugly fit and conform with the folds 9, and serve to clamp or press the abrasive cloth against the sides of the folds. 35 The flat supporting surfaces 13 on the flat inner working faces 8 of the shell serve as a backing for the folded portions of the abrasive disk and obviate the necessity of sharply bending or folding the disk at a right angle and thereby cracking or otherwise weakening the disk at this point. 40

The extension 4 is formed with flat side faces 25, to provide a gripping surface for a vise or the like, not shown, for retaining the shell in non-rotatable position during the grinding operation. 45 According to common practice, the valve 7 is provided with holes, or the like, 26, in the upper face thereof whereby the valve may be rotated by means of a suitable tool, not shown.

To assemble my device I seat the abrasive disk 50 14 and clamping spider 16 within the shell 2. The bushing 18 is then positioned within the bore 5 of the shell, thereby clamping the arms 24 of the spider 16 and disk 14 within the U-shaped folds 9. Clamp nut 21, threaded on the end of 55

bushing 18, and adapter or bushing 22 positioned within the bushing 18, serve to firmly retain the clamping spider and disk in position.

When it is desired to refinish or grind the face of a valve, the valve stem is inserted in the bore of the shell, and the face of the valve is pressed against the abrasive element. The valve is then rotated by means of a suitable tool, not shown. It is to be understood that when the grinding faces or points on the disk become worn, new faces may be readily presented by rotating the disk a suitable distance.

Having thus described my invention:

What I claim is:

15. 1. A tool for grinding valves comprising a conical grinding shell adapted to receive a valve therein, said grinding shell having substantially U-shaped folds therein, an abrasive disk adapted to cover the inside of said grinding shell and fit in said folds, a clamping element for clamping said abrasive disk in said grinding shell having arms adapted to fit into said folds for holding said abrasive disk in said shell.
20. 2. A tool for grinding valves comprising a conical grinding shell adapted to receive a valve having a stem therein, a bore in said conical grinding shell for receiving the valve stem therethrough, said grinding shell having outwardly extending substantially U-shaped folds therein, an abrasive disk removably mounted in said shell, a semi-rigid metal clamping element having V-shaped tapered arms for clamping said disk in said folds, and a member in said bore for retaining said clamping element in position within the folds.
25. 3. A tool for grinding valves comprising a conical grinding shell adapted to receive a valve and

valve stem therein, a bore in said shell for receiving the valve stem therethrough, said shell having substantially U-shaped outwardly extending folds therein, an abrasive disk removably mounted in said shell, a semi-rigid metal clamping member having V-shaped tapered arms adapted to fit in said folds for clamping the disk against said shell, and an adapter in said bore for retaining said clamping member in position within said shell.

4. A tool for grinding valves comprising a conical grinding shell adapted to receive a valve and valve stem therein, said shell having flat working surfaces thereon, said working surfaces having relatively small V-shaped grinding faces thereon, 15 said shell having substantially U-shaped folds therein, an abrasive disk removably mounted in said shell, a semi-rigid clamping member having V-shaped tapered arms adapted to fit in said folds for clamping the disk against said shell.

5. A tool for grinding valves comprising a conical grinding shell adapted to receive a valve and valve stem therein, said shell having substantially U-shaped folds therein, a plurality of flat working faces in said shell, said working faces being 20 ground down to form V-shaped valve engaging portions on said working faces, an abrasive disk removably mounted in said shell, said ground down portions adapted to provide a flat backing for the folded portions of said disk for preventing said disk from cracking at the folds, a semi-rigid clamping member having V-shaped tapered arms adapted to fit in said folds for clamping the disk against said shell.
